Primary Examiner — Stacia A Cadmus(74) *Attorney, Agent, or Firm* — Emerson, Thomson & Bennett, LLC; Roger D. Emerson(57) **CLAIM**

I claim the ornamental design for a vehicle wheel, as shown and described.

DESCRIPTION

FIG. 1 is a front view of a vehicle wheel, showing my new design;

FIG. 2 is a side view thereof; and,

FIG. 3 is a perspective view thereof.

The claimed design, as shown in FIGS. 1-3, is a new and ornamental design for a wheel to be used on automotive vehicles.
